GUARD DEVICE

John P. Dennebaum, Scranton, Pa.

Application June 12, 1935, Serial No. 26,281

12 Claims. (Cl. 256—13.1)

This invention relates to a guard device for protective purposes on highways and is designed primarily for positioning at the sides of a curve of a roadway; however, it is to be understood that a guard device, in accordance with this invention, may be employed at any point upon the roadway or in any connection for which it may be found applicable.

The invention has for its object to provide, in a manner as hereinafter set forth, a guard device constituting a cushioned abutment for arresting a vehicle from passing off of a roadway sidewise, more particularly when rounding curves thereby preventing accidents.

With the foregoing and other objects which may hereinafter appear, the invention consists of the novel construction, combination and arrangement of parts, as will be more specifically described and illustrated in the accompanying drawings, wherein are shown several embodiments of the invention, but it is to be understood that changes, variations and modifications may be resorted to which fall within the scope of the invention as claimed.

In the drawings:

Figure 1 is a top plan view of the guard device showing the installation thereof with respect to one side of a roadway,

Figure 2 is a fragmentary view in front elevation of the guard device,

Figure 3 is a vertical sectional view thereof,

Figure 4 is a perspective view of the resilient section of the suspension structure for the guard rail,

Figure 5 is a perspective view of the clamping section of the rail suspension structure,

Figure 6 is a section on line 6—6, Figure 5,

Figure 7 is a top plan view of a modified form,

Figure 8 is a fragmentary view in front elevation of the modified form,

Figure 9 is a vertical sectional view of the modified form,

Figure 10 is a perspective view of the resilient section of the suspension structure shown in Figure 7,

Figure 11 is a vertical sectional view of another modified form,

Figure 12 is a perspective view of the resilient section of the suspension structure of the form shown in Figure 11,

Figure 13 is a vertical sectional view of a further modified form,

Figure 14 is a fragmentary view in front elevation of the form shown in Figure 13,

Figure 15 is a perspective view of the resilient section of the suspension structure of the form shown in Figure 13,

Figure 16 is a perspective view of the clamping section of the suspension structure of the form shown in Figure 13,

Figure 17 is a perspective view of a modified form of the resilient section shown in Figure 13,

Figure 18 is a vertical sectional view and Figure 19 is a fragmentary view in front elevation of still another modified form of the guard device,

55

Figure 20 is a perspective view of the resilient member forming a part of the modification shown in Figures 18 and 19.

Figure 21 is a vertical sectional view of still another modified form of the guard device,

Figure 22 is a vertical sectional view of still another modified form of the guard device.

With reference to Figures 1 to 6, the guard device illustrated thereby includes a metallic guard rail 7 which has inturned curved end portions 8 and is of segmental contour in vertical section. The length of rail 7 will be as desired and is so disposed relative to a side 9 of roadway 10 that its convex face 11 will be arranged inwardly adjacent to such side. The rail 7 is imperforate. The rail 7 is clamped to a set of spaced resilient suspension structures 12. Each structure 12 is secured at its lower end to the front of a vertical support 13 anchored in the ground inwardly adjacent to roadway side 9. The lower ends of structures 12 are secured to the supports 13 in proximity to the ground level.

The structures 12 are of like form and each includes an upstanding resilient section 14 formed from a strap of metallic material having a vertically disposed lower end part 15, an intermediate part 16 extending upwardly from the upper end of part 15 at an outward inclination and an upper end part 17 of segmental contour in lengthwise section having its convex face bearing against the concave face of rail 7. The part 17 is eccentrically disposed with respect to the part 16 and a support 13. The top edge of part 17 is notched, as at 18. The part 17, in close proximity to its point of mergence in part 16, is formed with an opening 19. The part 15 is provided with a plurality of openings 20. The part 15 abuts the front of a support 13 and has its openings 20 register with the outer end of openings 21 formed transversely of support 13. Bolts 22 extend through the registering openings 20, 21 and have their heads 23 abut the front face of part 15. The bolts 22 extend beyond the rear face of support 13 and carry clamping nuts 24 which coact with the heads 23 for clamping the section 14 to support 13 to provide for the parts 16, 17 to be arranged in spaced relation to the support.

Each suspension structure 12 also includes a clamping section 25 formed of a strap of metallic material of less width than that of part 17 of section 14. The body part of section 25, indicated at 26, corresponds in length to that of part 17 of section 14 and is curved lengthwise to correspond to the curvature of part 17 of section 14. The concave face of body part 26 bears against the convex or front face 11 of rail 7. The body part 26 is of greater length than the width of rail 7. The section 25, at the top of body part 26, is formed with a rearwardly extending angle-shaped flange 27 formed of a horizontal leg 28 and a vertical leg 29 depending from the inner end of leg 28. The body part 26 in proximity to its lower end, is formed with an opening 30. The body part 26, in transverse section, is of segmental contour. When section 26 is in clamping position the leg 28 of flange 27 extends through notch 18 and seats upon the top edge of rail 7, leg 29 bears against the upper portion of the concave face of section 14 to form a quick detachable connection. The lower end of body part 26 depends below the bottom edge of rail 7 to an extent to have opening 30 align with opening 19 of section 14.

Each suspension structure 12 further includes a holdfast means for connecting sections 14 and 25 together in a manner to fixedly maintain the

body part 26 of section 25 in clamping engagement with the rail 7 and the part 17 of section 14 to tightly bear against the inner face of rail 7 whereby the rail 7 is prevented from bodily shifting relative to any one of the structures 12. The holdfast means consists of a bolt 31 extending through the openings 30, 19, having its head 32 bearing against the outer face of body part 26, its shank projecting from part 17 and a clamping nut 33 coacting with head 32.

The manner of setting up the suspension structures provides for them suspending the guard rail eccentrically in spaced relation relative to the front of the supports 13. On loosening the bolts of the suspension structures the guard rail 7 may be readily adjusted bodily lengthwise with respect to the set of spaced supports 13. The suspension structures provide cushioning means for the guard rail when the latter is impacted by a vehicle.

Referring to the modified form shown in Figures 7 to 10, the guard device includes a guard rail 34 of the desired length and width which is not curved transversely as is the rail 7, a set of spaced opposed vertical supports 35, only one shown, to be anchored in the ground and a set of resilient suspension structures 36, only one shown, each secured to and extended laterally from the front of a support 35.

Each support 35 is formed with a pair of spaced superposed parallel openings 37 extending transversely of and from the front to the rear face thereof. The upper opening 37 is arranged in proximity to the upper end of the support. The lower opening 37 is arranged between the upper opening 37 and the transverse median of the support.

Each suspension structure 36 includes a resilient section 38 formed of a vertically disposed resilient metallic cylinder 39 open at each end and split from its upper to its lower end to provide a pair of end edges 40, 41. The parts 42, 43 of the body of cylinder 39 bordering the edges 40, 41 respectively are arranged in overlapping relation. The upper portion of parts 42, 43 are provided with 45 registering openings 44, 45 respectively. The lower portion of parts 42, 43 are formed with registering openings 46, 47 respectively. The openings 44, 46 are to register with the front end of the openings 37 in a support 35. The top 50 edge of the front part of cylinder 39 is formed with a transverse notch 48. The front face of the front of section 39 is positioned against the rear face of rail 34.

Each suspension structure 36 also includes a 55 clamping section 49 of inverted yoke-shape form having its top 50 seated in notch 48, its front side 51 bearing against the outer face of rail 34 and its rear side 52 bearing against the inner face of the front of cylinder 39, its top 50 seated in 60 the top edge of the rail 34 and its sides 51, 52 depending below the bottom edge of rail 34 and cylinder 39. The sides 51, 52 are resilient and are formed in proximity to their lower ends with aligning openings 53.

Each suspension structure further includes a holdfast means for tightly securing the rail 34 and sections 38, 49 in clamped abutting relation whereby the rail 34 is prevented from bodily shifting relative to any one of said structures. 70 The holdfast means consists of a bolt 54 extending through the openings 53 having its head 55 bearing against the front face of side 51 of section 49 and carrying a clamping nut 56 to bind against the rear face of side 52 of section 75

of spaced upstanding supports 127, only one shown, and which are adapted to be anchored in the ground adjacent a side of a roadway. Each support 127 will be provided adjacent its upper end with an opening 127^a extending from its front to its rear face as shown in Figure 18. There is to be associated with the front of each support 127 a resilient suspension structure 128. The structures 128 are for the purpose of resiliently suspending a straight guard rail 129. The resilient suspension structures 128 are of like form and each includes an upstanding resilient section 130 of substantial oval contour in side elevation. The section 130 consists of a single length of strap metal bent in a manner to form a vertically disposed rear part 131, oppositely curved upper and lower parts 132, 133 respectively arranged in superposed spaced relation and extended outwardly from part 131, an inner front part 134 depending from the outer end of part 132 and an outer front part 135 extending upwardly from the outer end of part 133. The latter is of greater length than part 132. The part 135 is of materially greater length than and abuts the outer face of part 134. The part 135 is of greater length than part 131 and extends above the part 132. The part 131 has a central opening 136. The section 130, at the point of jointure of part 133 with part 135, is formed with a downwardly inclined opening 137. The top of part 135, centrally thereof, is formed with a notch 138. The part 135 is formed with opposite downwardly inclined top edge portions 139 leading from the side edges of notch 138 to the side edges of part 135. The opening 136 aligns with opening 127^a and extending through said aligning openings is a holdfast means 140 for anchoring section 130 in laterally extended relation with respect to the front face of support 127. Each resilient suspension structure 128 also includes an upstanding clamping section 141 formed from a strap of metallic material of less width and length than that of the strap from which section 130 is formed. The section 141 consists of a vertically disposed straight intermediate portion 142, a rearwardly directed angle-shaped upper end portion formed of a horizontal leg 143 and a vertical leg 144 depending from the rear end of leg 143 and a depending rearwardly curved lower end portion 145 formed with a downwardly inclined opening 146 aligning at its inner end with the outer end of opening 137. The leg 143 extends through notch 138. The leg 144 opposes the inner face of the upper portion of part 135 of section 130. The rail 129 is interposed between sections 130 and 141. The bottom edge of rail 129 is arranged above openings 131, 146. The angle-shaped upper end of section 141 connects the latter to the section 130. Extending through the openings 137, 146 is a downwardly inclined holdfast means 141 which coacts with the angle-shaped upper end of section 141 for securing the rail 129 to a resilient suspension structure 128. The lower inner corner of the rail 129 seats on a point of that part 65 of the holdfast means arranged between the sections 130, 141.

With reference to Figure 21, the resilient suspension structure indicated at 148 is of the same form as that of the suspension structure 128 with the exception that the resilient section 149 of structure 148 is of a different form than that of section 130 of structure 128. The section 149 includes a vertical rear part 150 having an opening 151, a bottom part 152 and a single front part 153 extending upwardly from the outer end of

part 152 and of greater height than that of part 150 to extend above the latter. The part 153 is formed similar to that of part 135 of section 130. The clamping section of structure 148 is designated 154. Otherwise than that as stated, the form shown in Figure 21 corresponds to that shown in Figures 18, 19 and 20.

With reference to Figure 22, the resilient suspension structure indicated at 155 is of the same construction as that of the suspension structure 128 with the exception that the resilient section 156 of structure 155 is of a different form than that of section 130 of structure 128. The section 156 includes a vertical rear part 157 having an opening 158, an upper part 159, a lower part 160 arranged outwardly with respect to part 159, an intermediate part 161 connecting the outer end of part 159 to the inner end of part 160 and a vertically disposed front part 162 extending upwardly from the outer end of part 160. The part 162 extends above parts 157, 159 and is constructed in the same manner as the part 135 of section 130 of structure 128. The coupling section of structure 155 is designated 163. Otherwise than that as stated, the construction of structure 155 will correspond to that of structure 128.

What I claim is:

1. In a guard device, a resilient element adapted to have its outer portion abut the inner face of a guard rail, means for anchoring said element directly against and in lateral suspended relation to an upstanding support, a coupling element adapted to abut the outer face of the guard rail, said elements having coacting interengaging parts at their upper ends for quickly detachably connecting them together to bear against the faces of the guard rail, and means carried by and coacting with said elements independently of the guard rail for clamping said elements and rail together to resiliently suspend the latter.

2. In a guard device, a resilient element adapted to have its outer portion abut the inner face of a guard rail, means for anchoring said element in lateral suspended relation against an upstanding support, a coupling element adapted to abut the outer face of the guard rail, said coupling element seating upon the top edge of the guard rail and seating within the top edge of the resilient element, thus forming a quick detachable connection, and means independent of the guard rail for clamping the elements together to resiliently suspend the rail.

3. In a guard device, an upstanding resilient element having a vertically disposed lower portion and its remaining portion extended outwardly from said lower portion, means for anchoring said lower portion against an upstanding support to dispose the said remaining portion in lateral suspended relation with respect to the support, a guard rail having its inner face abutting the upper part of the front face of said remaining portion, a clamping element bearing against the outer face and overlapping the top edge of said rail and interengaging within the top edge of said remaining portion, and means arranged below said rail, carried by and coacting with said elements for tightly clamping the rail and elements together to provide for said elements resiliently suspending the rail.

4. In a guard device, a resilient element, means for anchoring it in lateral suspended relation with respect to an upstanding support, a guard rail having its rear face positioned against the front of said element, a clamping element bearing against the outer face of said rail and having

49. The head 55, nut 56, sides 51, 52 coact to tightly clamp the rail 34 to a structure 36.

Each suspension structure 36 is secured against the front of a support 35 by superposed holdfast means 57, 58, one extending through that opening 37 which aligns with openings 44, 45 and the other extending through that opening 37 which registers with openings 46, 47. The pair of holdfast means 57, 58 anchors the suspension structure 36 to a support 35 whereby guard rail 34 is resiliently suspended in spaced relation with respect to a support 35.

When the bolts 55 are loosened, the rail 34 can be bodily adjusted in lengthwise relation with respect to a set of supports 35 without removing the rail from the suspension structures 36.

The modified form of guard device shown in Figures 11 and 12 includes a set of spaced upstanding supports 59 (only one shown) which are to be anchored in the ground, a guard rail 60 and a set of resilient suspension structures 61 for the rail 60. The latter is of the same form as the rail 34. Each support 59 is formed with a pair of superposed parallel openings 62, 63 disposed transversely of support 59 and extending from the front to the rear face of the latter. The opening 62 is arranged in proximity to the top of support 59. The opening 63 is arranged below and in proximity to the transverse median of support 59. The suspension structure 61 includes a resilient section 64 consisting of a split cylinder 65 of the same form and construction as that of cylinder 39 with the exception that cylinder 65 is of greater length than cylinder 39 and is formed centrally of its front and in proximity to its bottom edge with an opening 66. Otherwise than that as stated, cylinder 65 will be of the same form as that of cylinder 39. The notch in the top edge of cylinder 65 is indicated at 67. The front face of cylinder 65 bears against the rear face of rail 60. The structure 61 also includes a metallic clamping section 68 consisting of a strap-like body part 69 having an opening 70 adjacent its lower end aligning with opening 66. The inner face of body part 69 bears against the outer face of rail 60. The upper end of body part 69 terminates in a rearwardly directed angle-shaped flange 71 formed of a horizontal leg 72 and a vertical leg 73 depending from the rear end of leg 72. The latter seats in notch 67 and bears on the top edge of rail 60. The leg 73 abuts the inner face of cylinder 65. The body part 69 and cylinder 65 depend below the bottom edge of rail 60. The sections 64, 68 and rail 60 are tightly clamped together by a holdfast means 74 extended through openings 66, 70 and binding against the inner face of cylinder 65 and outer face of body part 69. The section 64 has a pair of upper registering openings 75 in registry with opening 62 and a pair of lower registering openings 76 in registry with opening 63. Holdfast means 77 extend through the registering openings 62, 75 and holdfast means 78 extend through registering openings 63, 76 for anchoring structure 61 to a support 59.

The modified form of guard device shown by Figures 13 to 16 includes a set of spaced upstanding supports 79 (only one shown) which are anchored in the ground and are of like form, a set of resilient suspension structures 80 (only one shown) of like form and a guard rail 81 of convexo-concave contour in vertical section. The convex face of rail 81 is designated at 82 and is

at the front of the rail 81. The rear or concave face of rail 81 is designated at 83.

The support 79 is formed with an opening 84 for the passage of holdfast means 85 to anchor structure 80 against the front face thereof.

The structure 80 includes a resilient section 86 formed from a metallic strap 87 having a vertically-disposed rear part 88, an upper intermediate part 89 of compound curvature depending in spaced relation to and from the upper end of part 88, a lower intermediate part 90 of compound curvature extending upwardly in spaced relation to and from the lower end of part 87, a curved upper front part 91 extending upwardly and rearwardly from the lower end of part 89 and spaced from the latter and a curved lower front part 92 extending downwardly and rearwardly from the upper end of part 90 and spaced from the latter. The lower end of part 89 is spaced from the upper end of part 90. The lower end of part 91 is spaced from the upper end of part 92. The upper end edge of part 91 is formed with a notch 93. The part 92, in proximity to its lower end, is formed with an opening 94. The front faces of the parts 91, 92 bear against the rear face 25 of rail 81. The rear part 88, centrally of its lengthwise median, is formed with an opening 88a for the passage of the holdfast means 85. The structure 80 also includes a clamping section 95 formed from a strap of metallic material of less 30 width than the strap which provides section 86. The section 95 includes a body part 96 of arcuate contour having its inner face bearing against the front face 82 of rail 81. The body part 96 is of greater length than the width of rail 80 and is 35 formed near its lower end with an opening 97 aligning with opening 94. The openings 94, 97 are arranged below the bottom edge of rail 81. The body part 96 merges at its upper end into a rearwardly extending downwardly inclined angle-shaped flange 98 formed with a downwardly inclined horizontal leg 99 terminating at its rear end in a depending forwardly inclined rear leg 100. The leg 99 extends through notch 93 and seats on the top edge of rail 81. The leg 100 bears 40 against the upper portion of the rear face of part 91 of section 86. Extending through the openings 94, 97 and bearing against the rear face of part 92 of section 86 and against the front face of body part 96 is a holdfast means 101 for tightly clamping the rail 81 to the sections 86, 95 whereby the rail will be prevented from shifting relative to structure 80 and will be arranged in suspended spaced relation relative to support 79. The holdfast means 101 of the structures 80 may be loosened and the rail 81 bodily shifted lengthwise with respect to the set of supports without removing the rail from structures 80.

The modified form of resilient section 102 shown in Figure 17 is to be substituted for the section 86 in the suspension structure 80. The section 102 is similar in construction to section 86 with the exception that the front upper part 103 of section 102 is provided on its rear face with a groove 104 opening at its top edge 105. The leg 100 of section 95 is to extend into groove 104. The leg 98 of section 95 is to seat on edge 105. Otherwise than is stated, the construction of section 102 will correspond to that of section 86. The rear, upper intermediate, lower intermediate and lower front parts of section 102 are designated 106, 107, 108 and 109 respectively. The openings in parts 106, 109 are designated 110, 111 respectively.

With reference to Figures 18, 19 and 20, the guard device illustrated thereby includes a series 75

- an integral part interengaging in the top edge of and depending within the resilient element, and means carried by and coacting with said elements for clamping them tightly against said rail to resiliently suspend the latter, said means being spaced from said rail.
5. In a guard device, a resilient element, means for anchoring it in lateral suspended relation with respect to an upstanding support, a guard rail having its rear face positioned against the front of said element, a clamping element bearing against the outer face of said rail and having an integral part interengaging in the top edge of and depending within the resilient element, and means carried by and coacting with said elements for clamping them tightly against said rail to resiliently suspend the latter, said means being spaced from said rail, and said elements having aligning openings below the rail for the passage of said means.
10. In a guard device, an upstanding element having a vertical lower part and a curved resilient upper part outwardly offset with respect to said lower part, means for anchoring said lower part against an upstanding support to position said upper part laterally suspended relative to the support, a guard rail of arcuate contour in cross section having its inner face positioned against the outer face of said upper part, a coupling element having its inner face bearing against the outer face of said rail, said elements having coacting interengaging parts at their upper ends, the coacting part of the clamping element seating on the top edge of said rail and in the top edge of said resilient upper part of said upstanding element, and means carried by and coacting with said curved upper part and the clamping element for tightly clamping the said elements and rail together to provide for said elements resiliently suspending the rail.
15. In a guard device, an upstanding element having a vertical lower part and a curved resilient upper part outwardly offset with respect to said lower part, means for anchoring said lower part against an upstanding support to position said upper part laterally suspended relative to the support, a guard rail of arcuate contour in cross section having its inner face positioned against the outer face of said upper part, a coupling element having its inner face bearing against the outer face of said rail, said elements having coacting interengaging parts at their upper ends, the coacting part of the clamping element seating on the top edge of said rail and in the top edge of the resilient part of the upstanding element, and means carried by and coacting with said curved upper part and the clamping element for tightly clamping the said elements and rail together to provide for said elements resiliently suspending the rail.
20. In a guard device, an upstanding element having a vertical lower part and a curved resilient upper part outwardly offset with respect to said lower part, means for anchoring said lower part against an upstanding support to position said upper part laterally suspended relative to the support, a guard rail of arcuate contour in cross section having its inner face positioned against the outer face of said upper part, a coupling element having its inner face bearing against the outer face of said rail, said elements having coacting interengaging parts at their upper ends, the coacting part of the clamping element seating on the top edge of said rail and in the top edge of the resilient part of the upstanding element, and means carried by and coacting with said curved upper part and the clamping element for tightly clamping the said elements and rail together to provide for said elements resiliently suspending the rail.
25. In a guard device, a resilient suspension element for a guard rail comprising a vertically disposed lower end part formed with superposed openings for the passage of holdfast means for anchoring said part to an upstanding support, an upstanding outwardly inclined intermediate part merging at its lower end into the upper end of said lower end part and an upstanding outwardly curved upper end part for abutting the inner face of the rail and merging at its lower end into the upper end of said intermediate part, said upper end part having a notch in its top edge, a curved coupling member adapted to bear against the outer face of the rail and provided with an angle-shaped flange at its upper end interengaging with said curved upper part for coupling said elements together, and means carried by and coacting with said elements for clamping the latter against the rail.
30. In a guard device, an upstanding support for anchoring in the ground, an upstanding resilient element including a vertically disposed lower end part positioned against the lower portion of the front face of said support, and upwardly extending outwardly inclined intermediate part merging at its lower end into the upper end of the said other part and an upwardly extending outwardly curved upper end part merging at its lower end into the upper end of said intermediate part and eccentrically disposed in spaced relation with respect to the front of said support, said upper part being formed with a notch in its top edge, a guard rail conforming in contour to that and having its rear face bearing against the front face of said upper part, a curved coupling element bearing against the outer face of said rail and having its upper end formed with a rearwardly extending angle-shaped part seated in said notch and bearing against the top edge of the rail and against the rear face of said curved upper end part, and means carried by and coacting with said curved upper end part and coupling element and arranged below the rail for tightly clamping the latter to said elements.
35. In a guard device, an upstanding resilient element formed of a split cylinder having the parts thereof bordering its split ends overlapping, said parts being arranged at the rear of the cylinder and provided with means for the passage of holdfast devices for anchoring the cylinder to an upstanding support, said cylinder adapted to have its front face bear against the rear face of a guard rail, said cylinder having the front part of its top edge formed with a notch, an inverted yoke-shaped element seated in said notch having one side bearing against the inner face of the cylinder and its other side adapted to bear against the outer face of the guard rail, said sides depending below said cylinder, and means carried by said sides below the guard rail and coacting with said sides for fixedly clamping said elements to the rail to suspend the latter.
40. In a guard device, a suspension element for and adapted to have a guard rail clamped thereto, said element consisting of a vertically disposed

rear part, oppositely disposed spaced upper and lower intermediate parts integral with and extending downwardly and upwardly respectively from the upper and lower ends of and spaced from said 5 rear part and oppositely disposed upper and lower front parts integral with and extending downwardly and upwardly respectively from the lower end of the upper intermediate part and the upper

end of the lower intermediate part, said front parts being spaced from said intermediate parts and having means for connecting them to a means for clamping the guard rail thereto, and said rear part having means for the passage of a holdfast device for anchoring the element suspendingly from an upstanding support. 5

JOHN P. DENNEBAUM.
